UNITED STATES PATENT OFFICE.

DIXON S. CARTER, OF BLOOMINGDALE, INDIANA.

BALL-CASTER.

957,303.

Specification of Letters Patent. Patented May 10, 1910.

Application filed August 27, 1909. Serial No. 515,094.

To all whom it may concern:

Be it known that I, DIXON S. CARTER, a citizen of the United States, residing at Bloomingdale, in the county of Parke, State 5 of Indiana, have invented certain new and useful Improvements in Ball-Casters; and I do hereby declare the following to be a full, clear, and exact description of the invention, such as will enable others skilled 10 in the art to which it appertains to make and use the same.

This invention relates to casters, more particularly to devices of this character known as ball-casters, and has for one of its objects 15 to provide a simply constructed device of this character, possessing non-conductive properties, so that the article of furniture to which it is attached is protected from the influence of electric currents.

With this and other objects in view, the invention consists in certain novel features of construction as hereafter shown and described and then specifically pointed out in the claims, and in the drawings illustrative 20 of the preferred embodiment of the invention. Figure 1 is a vertical sectional view of the improved device in one of its forms. Fig. 2 is a section on the line 2—2 of Fig. 1. Fig. 3 is a view similar to Fig. 1 showing 25 the improved device in another form. Fig. 4 is a section on the line 4—4 of Fig. 2. Fig. 5 is a view similar to Figs. 1 and 2, illustrating a modification in the construction.

The improved device may be employed 30 in connection with furniture of various kinds, but it is more particularly designed for use in connection with bedsteads, and may be employed in connection with metal or wood bedsteads without material structural changes, and for the purpose of illustration the improved device is shown arranged for both a metal and wood bedstead, to illustrate the operation more completely.

The improved device comprises a base or 45 body 10, of glass, porcelain, or other suitable material which is a non-conductor of electricity. When employed in connection with a metal bedstead the member 10 will preferably be circular and when employed in 50 connection with a wooden bedstead will preferably be square, as shown in Fig. 4. When employed in connection with a metal bedstead the body 10 is located beneath the corner posts, a portion of one of which is 55 shown at 11, and when employed in connection with a wooden bedstead the body 10

will be embedded for a short distance in the lower end of the post, a portion of one of which is represented at 12.

The body 10 is internally bored as shown 60 at 13, with the lower end of the bore contracted as shown at 14 to form a seat for a relatively large ball 15, the latter being of glass or like non-conductive material. By this means the ball is supported in position 65 and prevented from downward movement, but with a sufficient portion of the ball projecting below the member 10 to form the requisite bearing upon the floor which is indicated at 16. The member 10 is internally threaded at its upper portion as 70 shown at 17.

Bearing within the bore 13 is a plate or diaphragm 18, also of glass or other non-conductive material, and with its lower face 75 concaved, and fitting between the plate 18 and the ball 15 are bearing balls 19, the latter being also preferably of glass or like non-conductive material.

Fitting in the threaded portion 17 of the 80 member 10 is a tubular coupling member 20, preferably of metal, and provided with one or more screw-threads 21 at its lower end adapted to engage with the threads 17. By this means the member 20 may be adjusted 85 within the bore 13 by simply rotating it therein. Located between the lower end of the tube 20 and the plate 18 is a block 22 of yieldable material, such as relatively hard rubber. The upper end of the tubular member 20 is formed with a plurality of clefts 90 25, and the material of the member between the cavities is directed outwardly, to form a frictional clip device which will adhere with sufficient firmness to the inner walls of 95 the cavity 24 within the members 11 or 12 as the case may be, to hold the member 20 in position, and prevent it from dropping downwardly when the article of furniture is lifted from the floor. 100

When the device is applied to wooden structures, as shown in Fig. 3, the material between the clefts 25 of the member 20 is bent outwardly at the upper end to form points to enter the relatively soft material 105 12, as shown, and thus firmly couple the members. By this means the body 10 with its attachments is coupled with sufficient firmness to the leg members 11 or 12 to prevent the displacement of the devices when 110 the article of furniture is lifted.

The yieldable block 22 receives a large

share of the upward pressure, and thus relieves the glass members largely from strain, while at the same time producing a cushioning effect upon the structure above. The 5 block 22 being of rubber or like material is also a non-conductor of electricity, and contacts with the non-conductive members 10-18 and the balls 19 to effectually insulate the superstructure 11 or 12. The structure supported upon the improved device is therefore thoroughly insulated from electric currents, so that all danger of deleterious effects from lightning or other sources of electricity is obviated. The improved device 10 will also be found of advantage when the occupants of a bed are to be treated by electricity or galvanism, as the presence of the improved device will effectually prevent the undue elimination of the electric currents. 15 The improved device will also be found of great advantage in connection with electro-medico devices of various kinds, wherein it is requisite to insulate the chairs or like supports upon which the patients rest. 20 The improved device may be cheaply constructed, and the parts 10-18 and the balls 19 may be of any suitable non-conductive material, and it is not desired therefore to limit the device to any specific material for 25 these parts.

In Figs. 1 to 4 the portion of the tube 20 which contains the threads 21 is enlarged as shown so that the ball 15 is relatively large, but under some circumstances, the structure 30 shown in Fig. 5 may be employed, with the bore of the member 10 substantially uniform with the diameter of the smaller portion of the tubular member 20, and employing a smaller ball 15, but this structure does not

constitute a departure from the principle of 40 the invention, as the parts are substantially the same and perform precisely the same functions.

What is claimed is:—

1. A ball caster comprising a body of non-conductive material and formed with a longitudinal bore and with a ball seat in the lower end of the bore, a relatively large ball supported upon said seat, a bearing member of non-conductive material movable within 45 said body, a plurality of relatively small bearing balls between said larger ball and said bearing member, a coupling member, means for adjusting said coupling member within said bore, and a cushioning member 50 of non-conductive material between said coupling member and bearing member.

2. A ball caster comprising a body of non-conductive material and formed with a longitudinal bore, said bore having a ball 60 seat at one end and internally threaded at the other end, a relatively large ball supported upon said seat, a bearing member of non-conductive material movable within said body, a plurality of relatively small bearing 65 balls between said larger ball and said bearing member, a coupling member threaded at one end and engaging the threads of said body, and a cushioning member of non-conductive material between said coupling member and bearing member.

In testimony whereof, I affix my signature, in presence of two witnesses.

DIXON S. CARTER.
